PADDED SLEEPING DEVICE FOR
POSTURE CORRECTION

Paul J. Steinberger, Columbus, Ohio

Application July 14, 1951, Serial No. 236,833

1. Claim. (Cl. 128—78)

1

This invention relates to posture-maintaining and correcting appliances, having particular reference to an improved pad-provided appliance for use on the bodies of reclining persons, as those engaged in sleeping or resting on mattress-equipped beds or the like, whereby to maintain mechanically the bodies of such persons against loss of position or posture as a result of mattress-induced slumping of the body.

The object of the invention is to provide an appliance of this nature which may be worn by sleeping or reclining persons and so constructed as to provide improved bodily support for those wearing the same, particularly in the matter of maintaining the skeletal structure of the body in properly supported positions, even when various parts of the body tend to sink into a mattress or other yieldable base, and thereby place undesired strain on other portions of the body or its skeletal structure.

In certain relatively mild physical deformities, wherein the muscular or skeletal structure of the body is misshapen, under-developed, or otherwise abnormal, the corrective appliance of the present invention may be used while such a person sleeps or reclines in bed. In other relatively normal individuals, because of strain, poor posture, shallow breathing, or fatigue, the padded sleeping appliances herein provided serve to strengthen and correct physical weaknesses, providing sleeping comfort.

To these ends, the present invention consists in the provision of a garment or harness adapted to be worn on the body of a reclining person, the same being provided and equipped with shoulder, breast, abdomen, and buttocks pads of suitable size and shape to support the body in proper positions while the wearer when sleeping occupies a prone, downwardly facing position, or while sleeping on the back or one side or the other. These pads are so arranged as to automatically adjust the body to its correct posture, having the following factors in mind: (1) the tendency of the heavier parts of the body (the buttocks and shoulders) to sink rather deeply into the mattress; (2) the tendency of the articulated parts of the body (the spine, ribs, and shoulders) to be lifted out of position while the heavier parts are lowered; and (3) breathing, particularly taking cognizance of the fact that while it takes place normally under adverse circumstances, the same may be corrected and rendered more adequate if the chest were held expanded, instead of cramped by abdominal crowding or the rounding of the shoulders.

2

The present invention, further aims to provide a sleeping garment or the like which may be readily worn by a user with the same facility as a removable coat, in that it may be applied or removed with the same facility, and wherein the garment, or harness, if desired, includes appropriately located body-supporting pads which are so formed and arranged as to maintain correct posture of the user when sleeping on a mattress or other yieldable support.

For a further understanding of the invention, reference is to be had to the following description and the accompanying drawing.

In said drawing:

15 Fig. 1 is a perspective view of a padded sleeping garment formed in accordance with the present invention and disclosing the front thereof;

20 Fig. 2 is a rear elevational view of said garment when applied;

Fig. 3 is a transverse sectional view taken along the line 3—3 of Fig. 2;

Fig. 4 is a view in side elevation of the garment when the same is in use;

25 Fig. 5 is a detail front elevational view disclosing a modified form of the garment wherein the pads are rendered accessible by the use of sliding fasteners on the garment pockets.

Referring more particularly to the drawings, the garment or harness 1 of the present invention provides an article so formed as to cover the trunk of one's body and fit snugly thereover. This is done in order that the garment will not become twisted or out of position. Also, the garment may be worn with or without sleeves. Preferably, the garment is in the form of a coat, such as that of a regular pajama-type garment, or it may possess a vest-like form, adapted to be worn under ordinary night clothing. It will be understood that the garment may not be a full or complete one, but in the form of a partial garment, composed of a webbing, harness or strap arrangement providing pad-holding pockets 2 in which are inserted pads 3 of required size, shape, and yieldability.

30 The pads may be formed of any suitable soft or yieldable substance, such as cellular and non-cellular rubber, or from various fibrous materials customarily employed in the composition of pads or cushions. The pads may be placed in the pockets, and held therein with buttons or slide fasteners, as indicated at 4 in Fig. 5, or the pads may be permanently united with the supporting garment, as by sewing, cementing, or other means. As shown in Fig. 3, the pads possess their

maximum thickness in the centers thereof and taper to substantially a feather edge at their outer margins, so as to provide comfort. Preferably, the pads are arranged on the garment base in a manner providing a pair of shoulder or breast pads 5, a rearwardly located back pad 6, front and side abdomen-placed pads 7, and one or more rearwardly placed buttocks pads 8. The garment base serves to effect secure support of these pads in their relatively spaced order so that the operative positions thereof are maintained despite movement of the wearer while resting or sleeping.

As previously indicated, the purpose of these pads is to automatically adjust the body of the wearer to its correct position when reclining, having the following factors in mind:

(1) The tendency of the heavier parts of the body (the buttocks and shoulders particularly) to sink rather deeply into a mattress.

(2) The tendency of the articulated parts of the body (spine, ribs and shoulders) to be lifted out of position while the heavier parts are lowered.

(3) To improve breathing, particularly by holding the chest expanded instead of being cramped by other parts of the body.

The construction of the garment or appliance provides pads or cushions so arranged as to maintain mechanically the body of the wearer in sleeping positions correctly accounting for these factors.

As stated, the pads may be of various sizes and shapes, depending upon their position on the body, the size of the individual wearing the same, the body correction sought, and the personal preferences of the wearer. In most cases, a physician will prescribe the type of pads and their positions, but the wearer, by experience, might alter the pads in various ways after use in order to secure enhanced comfort.

When sleeping on the back, the pad shown at 8 extends over the entire area of the buttocks and is deep enough, when compressed by the body, to permit the spine to join the buttocks at the proper angle best adapted for health and comfort. In other words, the pad 8 is allowed to sink into the mattress, as indicated in Fig. 4, the approximate distance the body requires the mattress to recede, giving the result which would be gained by sleeping on a firm unyielding mattress or base, as is sometimes prescribed for arthritic persons.

The shoulder pad 6 on the center of the back of the garment or harness retains the spine to be in longitudinal alignment and also will prevent rounding of the shoulders, inducing normal unrestricted breathing when the wearer sleeps on his back.

When the wearer sleeps on his side, the abdominal pad 7, which is so formed as to extend around each side of the wearer supports the body at either side, so that the spinal structure will not arch in a downward direction at the small of the back as the result of the tendency of the hips and shoulders to tilt. The pad 7 might vary in thickness at the front and sides, depending upon the corpulence of the wearer. Usually it is rather thick for slender persons, while a corpulent person may require a comparatively light pad.

When sleeping face down, the pads on the upper front part of the garment, indicated at 5, serve to support the shoulders of the wearer, permitting the chest cavity to carry less body weight. The chest, therefore, remains deeper or enlarged because of this support, which tends to throw the shoulders back.

The pad on the abdomen, indicated at 1, may be of a thickness to support the spine in a proper manner and position the diaphragm for proper breathing with the wearer lying face down. In the event the wearer occupying this sleeping position is quite thin, a rather thick pad is required because the small of the back arches when there is no support at the abdomen. The size, shape, position, and thickness of the pads will depend upon the size of the wearer and the corrective measures sought. The garment, or harness, may be strictly utilitarian, or may be a part of a regular sleeping garment. It may be buttoned or may be elastic, without closure, and a crotch strap 9 may be used to maintain the garment in proper position.

The device has the advantage of being simple to apply, and when the pads are properly adjusted for a given person, little or no difficulty is thereafter encountered in the use of the device. The latter may be kept in a cleanly condition by the fact that the pads may be removed from the garment pockets whenever the garment is to be cleansed. The construction of the garment is essentially simple, and the same may be produced at relatively low cost. The removability of the pads enables pads of various thickness, shape or size to be employed as desired.

I claim:

A padded sleeping device for posture correction of reclining persons, comprising: a body-encircling garment having a front and a back, a pair of spaced breast-protecting pads mounted in spaced relation on the upper front part of said garment body; a single abdomen-protecting pad stationarily carried by and extending transversely across the front of the lower portion of said body beneath said breast pads; a single transversely extending buttock-supporting pad formed with the back of said garment and extending transversely thereof; and a single shoulder-supporting pad carried in the central upper back region of said body above said buttock pad, said abdomen and buttock pads extending around to the sides of the garment and terminating in contiguous and laterally offset relationship, said pads being engageable with the respective areas specified of the wearer's body and being of such thickness as to compensate for bed mattress recession produced by the weight of the wearer's body when in a reclining position on the mattress in maintaining normal posture of the wearer's body.
